ALEXANDER S. CHESSIN, OF NEW YORK, N. Y.

STABILIZING APPARATUS.

1,134,439.

Specification of Letters Patent.

Patented Apr. 6, 1915.

Application filed May 29, 1909. Serial No. 499,181.

To all whom it may concern:

Be it known that I, ALEXANDER S. CHESSIN, a subject of the Emperor of Russia, and resident of the borough of Manhattan, city, county, and State of New York, have invented certain new and useful Improvements in Stabilizing Apparatus, of which the following is a specification.

My invention relates to gyrostatic devices for preventing or reducing the oscillations of bodies which are normally in a state of unstable equilibrium or subject to oscillations or vibrations.

The invention is designed especially to prevent or reduce the rolling of ships, but is capable of numerous other applications, as for instance to aeroplanes, or to naturally unstable vehicles such as bicycles or monorail cars, or to conveyances which although stable are liable to oscillate or vibrate.

I am aware that the employment of gyrostats for stabilizing purposes is not novel broadly, but my invention, described in detail hereinafter, offers material advantages in construction and operation. More particularly, I am enabled to steady the structure by means of a single gyrostat, even when the vehicle is required to travel on curves.

One of the features of my invention consists in so regulating precession of the gyrostat that the stabilizing effect produced thereby will adjust itself automatically to the varying conditions of disturbance. Further, I provide such a connection between the gyrostat and the structure to be steadied that any tendency to disturb the equilibrium of the structure is automatically and instantaneously counteracted by the gyrostatic effect.

Reference is to be had to the accompanying drawing, in which—

Figure 1 is a front elevation of a gyrostat in which an external motor is employed, in accordance with my invention, for governing the precession; Fig. 2 is a side elevation of the same structure; and Fig. 3 is a side elevation of a structure of the same character but differing slightly from the one shown in Figs. 1 and 2.

A indicates the body of the structure to be steadied by the gyrostat, for instance a portion of the ship's hull.

B is a support pivoted to the body A about a normally horizontal axis C, which

in the case of a ship would extend lengthwise of the hull. To this support the gyrostat frame D is pivoted at E about a horizontal axis extending at right angles to the axis C, that is, transversely of the hull, in the special case mentioned. I have shown the axis C at a level considerably below that of the axis E, and this presents certain practical advantages, but the two axes C, E might be arranged otherwise. The bearings F of the axis E are adapted to engage plates or contact members G, having guided vertical movement in suitable portions of the body A and arranged to yield, to a limited extent, against the tension of the springs H. The plates or contact members G are adjustable vertically, as by turning nuts M, so as to regulate the amount of play between said contact members and the bearings F. In the frame D is journaled to turn about a vertical axis or spindle I the rotary gyrostat member J, of any suitable construction. Usually this gyrostat member would consist of a heavy body or wheel combined with a motor (such as an electric motor) for rotating it. The spindle I and member J constitute a rotor, while the support B and frame D with axis E and bearings F constitute a carrier capable of swinging relatively to the body A. The carrier and rotor together constitute what I will call a gyrostat structure.

In order to make clear certain terms used in my claims which are, perhaps, too technical to be taken for granted, I will here explain their meaning. If a body is free to turn about a single axis, it is said to possess one degree of rotational freedom. If it is free to turn about two mutually perpendicular axes, it is said to possess two degrees of rotational freedom. If it is free to turn about three mutually perpendicular axes, it is said to have three degrees of rotational freedom. No body can possess more than three degrees of rotational freedom. According to these definitions my rotor possesses three degrees of rotational freedom, its frame (as, D) possesses two degrees and, finally, the support (as, B) possesses one degree of rotational freedom.

The center of gravity of the structure formed by the rotary gyrostat member J, its spindle I, and frame D, is generally below the axis E (as in Fig. 1, where the lower part of the frame D is shown heavier than

its upper part), but I do not wish to restrict myself to this specific arrangement. The advantage of having the center of gravity below said axis, consists in changing the 5 equilibrium from an unstable one to a stable one in the particular case of the body A making a turn about a vertical axis in the direction opposite to that in which the rotor of the gyrostat rotates.

- 10 In some cases, for instance, in heavy weather, it might be desirable to hold the gyrostat in its extreme position until the ship is well on her way to the upright position, to prevent the gyrostat from impeding 15 the returning swing of the ship. Fig. 2 shows an arrangement for this purpose. Each of the straps Q is secured at one end to the frame D, and at the other end to a spring-roller R of the well-known character, 20 to keep the straps taut and also limit their outward movement. Each strap passes adjacent to a brake shoe or locking member S, which may be thrown into operative position by suitable lever mechanism T.
- 25 In order to positively give the gyrostat a precession of predetermined speed, the following additional arrangement is provided: The axes or trunnions E (rigid with the frame D) are extended and carry mutilated 30 gears E' rigid with said trunnions. These gears are adapted to mesh with driving pinions G' rotated continuously by any suitable mechanism, such as driving belts Z. The two pinions G' should rotate in opposite directions, and the toothed portions of the two gears E' should occupy different positions in such a manner that Fig. 2 may be described as showing the gears E' and G' on one side of the device, or those on the other 35 side, looking toward the center. If the body A swings transversely, the mutilated gear on one side will mesh with its pinion G', and the engagement of the bearing F on the same side with the corresponding contact 40 plate G will relieve the pressure between the gear teeth. The precessional speed depends, of course, on the action of the meshing gears E', G'. It will be obvious that by varying the speed of the driving pinion G, and the 45 ratio between the diameter and that of the mutilated gear, this precession might be given any desired value. Of course, these moving driving devices such as gears G' are driven at a comparatively low speed, corresponding to that of the desired precessional motion. Since this speed may be properly regulated, it follows that the precession may be accurately regulated and controlled, and since the moving driving device such as 50 gears G' is driven continuously, so that they rotate even before being engaged by the mutilated gears E', it follows that the steadyng effect takes place instantaneously upon said contact members or gears coming 55 into engagement. In the particular case 60

illustrated by Figs. 1 and 2, the precession produced by the moving driving device such as gears G' would be made over-normal. On the return swing of the ship, the gear E' and bearing F previously in contact are 70 lifted off, and the bearing F on the opposite side comes in engagement with its contact plate or contact member G, while the teeth of the gear G' on that side are not in position to mesh. Consequently, the return precession is normal, that is to say, it is due simply to the pressure of plate G against the bearing F. Of course, the frame D is not allowed to swing far enough to bring the teeth of the gear G' against the smooth portion of the mutilated gear E', the contact plate G having also the function of a stop for this purpose. The reactive forces resulting from the precessional motion right 80 of the ship. 85

The precessional speed, governed by the meshing gears, may be adjusted to meet the varying demands of more or less heavy rolling due to varied conditions of the sea, the necessary reactive forces being greater in a 90 heavy than in a light sea; or to meet the changes in the ship's tonnage which affect its rolling momentum; or to enable the same apparatus to be transferred to a ship of a different tonnage, etc. The regulation of 95 the precession may also be effected in a materially different manner, as for example in the construction shown in Fig. 3, in which a less rapid damping of oscillation results. It is well known that the maximum effect of 100 the gyrostat in precessing normally, does not coincide in time with the maximum speed attained by the rolling motion of the ship (which speed generally reaches its maximum at the moment the ship passes through 105 the upright position). It is therefore of advantage in some cases, to so proportion the precessional effect as to distribute it more uniformly over the period of one or more swings. In Fig. 3 the construction is 110 the same as in Figs. 1 and 2, except that the gears E² are toothed equally on both sides of a vertical line drawn through their centers at the time the ship is in an upright position. The purpose of this arrangement is to obtain 115 a meshing of one gear E² with the corresponding pinion G' during the outward swing, and a meshing of the other gear during the return swing, the precessional speed during both swings being generally made 120 under-normal by properly regulating the speed of the driving pinions G'. 125

I claim as my invention:

1. A gyrostat structure comprising a rotor mounted to turn about a normally vertical axis, a frame in which said rotor is journaled, and a support connected with said frame by a normally horizontal pivotal connection, the combined center of gravity of the rotor and frame being below the point 130

- of intersection of the rotor axis with said normally horizontal pivotal connection, in combination with a body to which said support is connected loosely to swing about a 5 normally horizontal axis perpendicular to the first named horizontal axis, and members carried by said body and normally out of contact with the gyrostat structure but adapted to engage the same when said body 10 swings and to produce a precession of the rotor.
2. The combination of a rotor mounted to turn about a normally vertical axis, a frame in which said rotor is journaled, a body connected with the frame by a universal joint comprising a normally horizontal pivotal connection with the frame, the joint center of gravity of the rotor and frame being below the point of intersection of the rotor 15 axis with the said normally horizontal pivotal connection, and members carried by the body and normally out of contact with the gyrostat structure but arranged to engage one of the above mentioned elements of the 20 gyrostat structure when said body swings and to produce a precession of the rotor.
3. The combination of a carrier comprising a frame and a support having a normally horizontal pivotal connection with the 25 frame, with a rotor journaled in said frame, the combined center of gravity of the rotor and frame being below the point of intersection of the rotor axis with said normally horizontal pivotal connection, a body with 30 which the support is connected by a normally horizontal pivotal connection perpendicular to the first named pivotal connection, and members carried by the body and normally out of engagement with the carrier but adapted to engage the same when 35 said body swings to produce a precession of the rotor.
4. A gyrostat structure comprising a rotor mounted to rotate about a normally vertical axis, a frame in which said rotor is journaled, and a support having a pivotal connection with said frame, the joint center of gravity of the rotor and frame being below the axis connecting the frame with the 45 support, in combination with a body to which said support is pivoted, and members carried by said body and normally out of contact with the support but adapted to engage the same when said body swings and 50 to produce a precession of the rotor.
5. The combination with a body, of a gyrostat structure comprising a support mounted to swing relatively to the body, a frame mounted on said support to swing about an 55 axis at right angles to that of the support, and a rotor mounted to turn in said frame about a normally vertical axis, the joint center of gravity of the rotor and frame being below the axis connecting the frame with the 60 support, and members carried by said body 65 and normally out of contact with the gyrostat structure but adapted to engage the same when said body swings to produce a precession of the rotor.
6. The combination with a body, of a gyrostat structure comprising a carrier mounted to swing relatively to the body, and a rotor mounted to rotate in said carrier about a normally vertical axis, contact members carried by said body eccentrically with respect to the rotor axis and normally out of contact with the gyrostat structure but adapted to engage it when the body swings, and yielding devices for checking the impact at the time of such engagement. 70
7. The combination with a body, of a gyrostat structure comprising a carrier and a rotor journaled therein, said carrier being connected with the body in such a manner as to give the rotor three degrees of rotational freedom, movable driving members carried by the body and normally out of contact with the gyrostat structure but adapted to engage portions thereof as the body swings, and means for moving said 75 driving members.
8. The combination of a gyrostat structure comprising a carrier and a rotor journaled therein, with a body with which said structure is connected in such a manner as to give the rotor three degrees of rotational freedom, contact members carried by said body eccentrically with respect to the rotor axis and normally out of contact with the gyrostat structure but adapted to engage 80 portions thereof as the body swings, and yielding devices for checking the impact at the time of such engagement.
9. The combination of a gyrostat structure comprising a carrier and a rotor journaled therein, with a body with which said structure is connected in such a manner as to give the rotor three degrees of rotational freedom, contact members carried by said body eccentrically with respect to the rotor's 85 axis and normally out of contact with the gyrostat structure but adapted to engage portions thereof as the body swings, and yielding devices connected with said contact members for checking the impact at the 90 time of such engagement.
10. The combination of a body, a gyrostat structure connected therewith and moving devices carried by the body and normally out of engagement with the gyrostat structure, but adapted to engage portions thereof as the body swings to give the gyrostat a 95 precessional movement.
11. The combination of a body, a gyrostat structure connected therewith in such a manner as to give the rotor of the gyrostat three degrees of rotational freedom, and provided with toothed engaging portions, and driving pinions carried by the body and normally out of engagement with said 100

toothed engaging portions, but adapted to engage them as the body swings to give the gyrostat a precessional movement.

12. The combination of a body, a gyrostat structure connected therewith in such a manner as to give the rotor of the gyrostat three degrees of rotational freedom, and provided with toothed engaging portions mounted to turn relatively to said structure, and driving pinions journaled on the body and normally out of engagement with said portions of the gyrostat structure, but adapted to engage them as the body swings to give the gyrostat a precessional movement.

13. The combination with a body, of a gyrostat structure connected therewith movably, and continuously driven actuating members carried by said body and normally out of contact with the gyrostat structure, said structure being provided with portions adapted to engage said actuating members when the body swings, to produce a precession of the gyrostat.

14. The combination with a body, of a gyrostat structure connected therewith movably, and continuously rotating actuating members carried by said body and normally out of contact with the gyrostat structure, said structure being provided with portions adapted to engage said actuating members when the body swings, to produce a precession of the gyrostat.

15. The combination, with a body, of a gyrostat structure connected therewith movably, and independently actuated, continuously moving means for automatically producing precession.

16. The combination, with the body, of a gyrostat structure connected therewith, movably and independently actuated, continuously moving means for producing precession of predetermined speed.

17. The combination with a body, of a gyrostat structure consisting of a support mounted to swing relatively to said body, a gyrostat frame mounted on said support about an axis at right angles to that of the support, a gyrostat rotor mounted to rotate in said frame, movable driving members carried by said body and normally out of contact with the gyrostat structure but adapted to engage the support when said body swings and means for actuating said members to produce a precession of the gyrostat.

18. The combination with a body, of a gyrostat structure consisting of a support mounted to swing relatively to said body, a gyrostat frame mounted on said support to swing about an axis at right angles to that of the support, a gyrostat rotor mounted to rotate in said frame, and contact members movable on said body and normally out of contact with the gyrostat structure but adapted to engage the said structure as the

body swings and to produce a precession of the gyrostat.

19. The combination with a body, of a gyrostat structure comprising a support mounted to swing relatively to the body, a gyrostat frame mounted on said support to swing about an axis at right angles to that of the support, a gyrostat mounted to rotate in said frame, and moving devices carried by said body and normally out of engagement with the gyrostat structure but adapted to engage it as the body swings and to give the gyrostat precessional movement.

20. The combination with a body, of a gyrostat structure comprising a support mounted to swing relatively to the body, a gyrostat frame mounted on said support to swing about an axis at right angles to that of the support, a gyrostat mounted to rotate in said frame, the latter being provided with toothed engaging parts, and driving pinions carried by the body and normally out of engagement with said toothed parts but adapted to engage them as the body swings, to give the gyrostat precessional movement.

21. The combination with a body, of a gyrostat structure comprising a support mounted to swing relatively to the body, a gyrostat frame mounted on said support, to swing about an axis at right angles to that of the support, a gyrostat mounted to rotate in said frame, the latter being provided with toothed engaging parts, mounted to turn, and driving pinions journaled on the body, and normally out of engagement with said parts of the gyrostat structure but adapted to engage them as the body swings, to give the gyrostat a precessional movement.

22. The combination with a body, of a gyrostat structure comprising a support mounted to swing relatively to the body, a gyrostat frame mounted on said support to swing about an axis at right angles to that of the support, a rotor mounted to rotate in said frame, driving members carried by said body and normally out of engagement with the gyrostat structure but adapted to engage the said structure, when the body swings, and contact members having yielding devices for checking the impact at the time of such engagement.

23. The combination with a body, of a gyrostat structure comprising a support mounted to swing relatively to the body, a gyrostat frame mounted on said support to swing about an axis at right angles to that of the support, a rotor mounted to rotate in said frame, moving members carried by the body and normally out of contact with the gyrostat structure but adapted to engage the same as the body swings, and locking devices for temporarily preventing the movement of the gyrostat structure relatively to the body.

24. The combination with a body, of a

carrier mounted to swing on said body, a gyrostat rotor mounted on said carrier, movable members carried by said body and normally out of engagement with the carrier but adapted to engage it when said body swings, and means for driving said members to produce a precession of the gyrostat.

25. The combination, with a body, of a gyrostat structure connected therewith mov-
10 ably, and independently actuated continu-
ously moving means for automatically pro-
ducing precession and for controlling the
speed of said precession.

26. The combination of a body, a gyro-
15 stat structure connected therewith in such a

manner as to give the rotor of the gyrostat three degrees of rotational freedom, moving members carried by the body and normally out of engagement with the gyrostat structure, but adapted to engage portions thereof 20 as the body swings, and locking devices for temporarily preventing movement of the gyrostat structure relatively to the body.

In testimony whereof I have signed this specification in the presence of two subscri- 25
ing witnesses.

ALEXANDER S. CHESSIN.
